UNITED STATES PATENT OFFICE

JOHN H. HOFFMAN, OF PITTSBURGH, PENNSYLVANIA, ASSIGNOR OF ONE-HALF TO
WILLIAM B. ANKERSTRAN, OF NEW YORK, N. Y.

FEEDER FOR TYPE-CASTING MACHINES

Application filed March 1, 1930. Serial No. 432,384.

The invention relates to automatic feeders for type casting machines of the kind employing a tilting pot into which a bar or pig of type metal is fed automatically to maintain the molten metal in the pot at approximately a constant level. The invention has for its objects the provision of an improved apparatus of the kind specified in which the tilting movement of the pot is utilized to give the pig its downward feed and in which such feed is controlled by the level of the metal in the pot. A further object is the provision of a feed apparatus of simple construction, applicable to any standard type casting machine, not liable to get out of order, and which will operate with certainty and precision. One embodiment of the invention is illustrated in the accompanying drawing, wherein:

Figure 1 is a side elevation of a part of a type casting machine with the improved feeder applied thereto. Fig. 2 is a front elevation. Fig. 3 is a section on the line III—III of Fig. 1. Fig. 4 is an enlarged plan view of the escapement device. Fig. 5 is a side elevation of the construction shown in Fig. 4 with the casing broken away to more clearly show the parts therein. And Figs. 6 and 7 are end elevations of the structure of Figs. 4 and 5.

Referring first to Figs. 1 to 3, 1 is the usual melting pot of a linotype machine pivotally supported on the shaft 2 and adapted to swing from the full line position of Fig. 1 to the dotted line position, suitable means being provided for accomplishing the movement for each casting operation. Extending transversely of the pot is one of the frame members 3 of the machine, and on this is mounted a clamp 4 having an upwardly extending pipe or standard 5. Carried upon this pipe is a bracket 6 held in any desired position of vertical adjustment by means of a set screw. On this bracket is mounted the box or casing 7 for the escapement and feed control mechanism later described. Mounted upon the upper end of the standard is a second bracket 8 also held in any desired position of vertical adjustment by means of a set screw. The bracket

8 is provided with a pair of pulleys 9, 9 through which extends a chain 10 having a hook 11 which engages the upper end of the pig or bar 12 of type metal, the lower end of which dips into the molten metal 13 in the melting pot. The other end of the chain extends into the casing 7 and there passes around the sprocket 14 and the pulley 15 (Fig. 7). The chain then passes over the edge of the casing forming the loop 17 and being secured at its extreme end to the bottom of the casing, as indicated in Fig. 7.

The sprocket 14 is mounted on a shaft 18, the other end of which carries the escapement wheel 19, both the sprocket and wheel being secured to the shaft so as to turn therewith. The rotation of the wheel 19 is governed by the bars 20 and 21 pivoted respectively on the shafts 22 and 23 and yieldingly pulled toward each other by the springs 24 and 25, the spring 24 being secured to the hub of the bar 21 and the spring 25 being secured to the hub of the bar 20. The movements of the bars 20 and 21 are governed by the arms 26 and 27 secured to the shaft 28 so as to turn therewith, such arms having their free ends in engagement with the pins 29 and 30 projecting laterally from the bars 20 and 21. The shaft 28 is journaled in the casing with one end projecting through the side of the casing and having secured thereto the rocking arm or lever 31. Pivoted on the side of the arm 31 is a hook member 32 with a supporting link 33 having a pin and slot connection 34 with the side of the casing, so that the hook member is free to swing upward, but is held against downward movement.

Carried by the edge of the pot 1 is a bracket 35 (Figs. 2, 3, 5 and 7) on which is mounted the lever 36. The inner end of the lever is connected to a float 37 lying in the pot by means of a link 38, so that the position of the outer end of the link is regulated by the level of the metal in the pot. When the level of the metal is at the point shown in the drawings, the end of the lever lies below the hook 39 of the member 32, so that on the movement of the pot to the left bringing the lever 36 to the dotted line position A, there is no actua-

tion of the member 32 and no movement of either of the escapement bars 20 and 21. If, however, the level of the metal in the pot drops below the level shown, thus raising the outer end of the lever 36, such lever will, on the movement of the pot to the left engage the hook 39, thus rocking the arm 31 so that the arms 26 and 27 are rocked upward releasing the bar 20 from the tooth of the escapement wheel 19 and at the same time permitting the bar 21 to move up so as to catch the next tooth of the wheel. The release of the wheel by the bar 20 permits the wheel 19 to rotate in the direction of the arrow (Fig. 6) 10 a distance equal to the length of one-half of a tooth, at which time the bar 21 engages the next tooth 40 (Fig. 6). This movement of the wheel permits the shaft 28 to rotate slightly, thus lowering the pig 12 to supply 15 more metal to the pot. On the movement of the pot back to the right to the starting position, a bar 41, also secured to the top of the pot 1, engages the lever 31, thus rocking the shaft 28 and arms 26 and 27 to return them to the 20 position of Fig. 5. This releases the bar 21 from the wheel 19 and causes the bar 20 to engage it again. This permits the wheel 19 to again rotate the distance of one-half of a tooth, so that on each complete oscillation of 25 the pot, the wheel 19 is permitted to move ahead a distance equal to the length of one tooth, and the pig 12 is lowered correspondingly. The escapement is thus operated whenever the level of the metal in the pot 30 drops below a predetermined level, which can be regulated by adjusting the vertical position of the casing 7 and the parts carried thereby on the standard 5. When the level of the metal is at or above the predetermined 35 level, the outer end of the lever 36 lies at non-engaging position with respect to the hook arm 32, so that the back and forth movement of the pot has no effect upon the escapement, and the pig 12 remains in fixed position until 40 the level of the metal in the pot is lowered to the level which it is desired to maintain.

What I claim is:

1. In a type metal casting machine having a tilting melting pot, a toothed escapement wheel, a pair of escapement bars for controlling the movement of the wheel arranged to alternately engage the wheel and prevent its rotation but permitting a limited rotation during the shifting of the fingers, a 50 rocker arm for causing one bar to engage the wheel and release the other therefrom, flexible means governed by the movement of the wheel for supporting a pig of type metal above the pot so that the pig is fed downward 55 into the pot by the movement of the wheel, a float in the pot, an arm pivoted on the pot having one end connected to the float and the other end positioned so as to move said rocker arm in one direction when the level of the 60 metal in the pot drops below a certain level,

and another arm fixed on the pot and adapted to engage the rocker arm and move it back to starting position on the reverse movement of the pot.

2. In a type metal casting machine having a tilting melting pot, a toothed escapement wheel, a pair of movable fingers for restraining the movement of the wheel arranged so that when one finger engages the wheel, the other is disengaged therefrom, 70 flexible means for supporting a type metal pig above the pot having one portion thereof restrained by the wheel so that the rotation of the wheel permits the pig to be fed downward into the pot, a member operated by the tilting of the pot in one direction for moving one finger out of engagement with the wheel while the other is caused to engage it, means for bringing the fingers back to their 75 first position on the reverse movement of the pot, and means controlled by the level of the metal in the pot for governing the actuation of said member.

3. In a type metal casting machine having a tilting melting pot, a toothed escapement wheel, a pair of movable fingers for restraining the movement of the wheel arranged so that when one finger engages the wheel the other is disengaged therefrom, flexible 90 means for supporting a type metal pig above the pot having one portion thereof restrained by the wheel so that the rotation of the wheel permits the pig to be fed downward into the pot, a rocker arm operated by the tilting of the pot in one direction for moving one finger out of contact with the wheel while the other is caused to engage it, and means 95 operated by the reverse movement of the pot for bringing the fingers back to their first position.

4. In a type metal casting machine having a tilting melting pot, a toothed escapement wheel, a pair of movable fingers for restraining the movement of the wheel arranged so that when one finger engages the wheel the other is disengaged therefrom, flexible means for supporting a type metal pig above the pot having one portion thereof restrained by the wheel so that the rotation of the wheel permits the pig to be fed downward into the pot, a float in the pot, a member whose 100 position is regulated by the float, an arm operated by the member when the pot tilts in one direction for moving one of said fingers out of engagement with the wheel and the other finger into engagement with it, and means for bringing the fingers back to their first position on the reverse movement of the pot, said member being arranged so that when the level of the metal in the pot drops below a certain point such member will not engage and operate said arm.

5. In a type metal casting machine having a tilting melting pot, a toothed escapement wheel, a pair of movable fingers for restrain-

ing the movement of the wheel arranged so that when one finger engages the wheel the other is disengaged therefrom, flexible means for supporting a type metal pig above the pot having one portion thereof restrained by the wheel so that the rotation of the wheel permits the pig to be fed downward into the pot, a float in the pot, a member whose position is regulated by the float, means operated by the member when the pot tilts in one direction for moving one of said fingers out of engagement with the wheel and the other finger into engagement with it, and a stop member on the pot for bringing the fingers back to their first position on the reverse movement of the pot, said means which is operated by said member being so arranged that when the level of the metal in the pot drops below a certain point, such member will not engage said means.

6. In a type casting machine having a tilting melting pot, a flexible member for supporting a type metal pig above the pot, an escapement wheel with a series of stop elements arranged around the center of rotation thereof, a pair of escapement fingers arranged to engage said elements, means operated by the tilting movement of the pot for moving one of the fingers into engaging position with respect to said elements while the other is moved out of engaging position, and then reversing their movement, and means controlled by the level of the metal in the pot for governing the operation of said means.

7. In a type casting machine having a tilting melting pot, a flexible member for supporting a type metal pig above the pot, an escapement wheel with a series of stop elements arranged around the center of rotation thereof, a pair of escapement fingers arranged to engage said elements, means operated by the tilting movement of the pot for moving one of the fingers into engaging position with respect to said elements while the other is moved out of engaging position, and then reversing their movement, and a float in the pot arranged to cause said means to operate when the level of the metal drops below a certain point and to move said means to non-operative position when said level rises above a certain point.

In testimony whereof, I have hereunto subscribed my name this 28th day of February, 1930.

JOHN H. HOFFMAN.
